UNITED STATES PATENT OFFICE.

WALTER L. WIDLAR, OF LAKWOOD, OHIO, ASSIGNOR TO THE JIFFY JACK COMPANY, OF CLEVELAND, OHIO, A CORPORATION OF OHIO.

JACK.

1,241,590.

Specification of Letters Patent.

Patented Oct. 2, 1917.

Application filed October 20, 1916. Serial No. 126,707.

To all whom it may concern:

Be it known that I, WALTER L. WIDLAR, a citizen of the United States, residing at Lakewood, in the county of Cuyahoga and State of Ohio, have invented a certain new and useful Improvement in Jacks, of which the following is a full, clear, and exact description, reference being had to the accompanying drawings.

10 This invention relates generally to lifting jacks and more particularly to an automobile jack.

15 The object of the invention is to provide an automobile lifting jack of pressed sheet metal, the various parts being constructed and arranged with the idea of obtaining an exceedingly light jack and at the same time one that will be strong, durable and easily operated to either lift or lower a load step by step.

20 Another object is to provide a step by step jack in which only one spring is employed and a still further object is to provide a jack in which the lifting bar can be pulled out to its maximum height, or dropped back instantly, when desired.

25 With these objects in view the invention consists in the novel construction and arrangement of the various parts as herein-30 after fully described and pointed out in the claims.

35 In the drawings forming a part of this specification, Figure 1 is a perspective view of the lifting jack illustrating one embodiment of my invention; Fig. 2 is a vertical sectional elevation showing the parts arranged ready for the lifting operation; Fig. 3 is a similar view showing the parts during the lifting operation and Fig. 4 is a view showing the position of the parts at the end of the downward movement of the lever; Figs. 5, 6 and 7 are sectional elevations showing the positions of the parts during the lowering operation; Fig. 8 is a 40 detail sectional view on the line 8--8 of Fig. 7; Fig. 9 is a detail sectional view on the line 9--9 of Fig. 7 and Fig. 10 is a detail sectional view on the line 10--10 of Fig. 7; and Fig. 11 is a detail perspective 45 view of the lever head, pawls and cam, the pawls and cam being shown separated and spaced from the lever head.

50 In carrying out my invention I provide a standard 10 which is preferably made from a single piece of sheet metal folded or

bent upon itself so as to provide parallel sides and a closed back and if desired a sheet metal front 10^a can be inserted between and connected to the forward edges of the side members. The sheet metal 60 standard 10 is securely connected to a sheet metal base 11, the central portion of which is elevated to provide a convenient part for the connection of the standard, while the outer edges are flat in order to provide a 65 broad firm base.

Working in the box like standard 10 is the lifting bar 12, also of sheet metal, and folded longitudinally upon itself and made ratchet teeth 13, a cap block or head 14 being arranged at the top of the bar and having the depending portion thereof secured between the members of the bar by means of pin 14^a, as most clearly shown in Fig. 9.

The back of the lift bar is swelled or 75 curved as shown at 15, which swelled or curved portion works into the grooved or channeled portion 16 of the standard and in practice I prefer to split the lift bar at the bottom and turn the ends outwardly as 80 shown at 17. The sides of the standard are pressed inwardly at 18 so as to engage the ends 17 and prevent the lift bar being withdrawn from the standard.

85 The ratchet teeth of the lift bar are engaged by the pawls 19 and 20 pivoted respectively upon the pins 21 and 22 between the jaws 23 of the lever 24. The pawls 19 and 20 are also of stamped metal, the pawl 19 being longer than the pawl 20, and the 90 pin 21 which serves as a pivot for the pawl 19 also serves as a pivot for the lifting lever, this pin passing through the standard and having a cotter pin through one end thereof to prevent dislocation.

95 The lever 24 is made of two pieces of sheet metal rolled together at their edges and for convenience this lever is shortened as shown and a wooden handle 25 inserted in the socket end thereof. The pin 22 serves as a 10 pivot for the pawl 20 and passes through the end of the lever in advance of the pin 21 and therefore transmits the power of the lever to the lifting bar.

The pin 21 also serves as a pivot for a 10 cam 26 which operates in combination with the pawls for the purpose of throwing them into and out of engagement with the ratchet teeth of the lifting bar at the proper time, and this cam 26 is shifted back and forth 11

from a raising to a lowering position and vice versa by means of a shifting lever 27 pivoted to the standard near the lower end of the same and operating at its inner end upon a forked plate 27^a, to which is attached a spring rod 28, having its upper end in engagement with the apertured lug 29 of the cam 26.

By throwing the shifting lever 27 up as shown in Figs. 1, 2 and 3 the spring rod is bowed forwardly and throws the cam to its forward or raising position, and when the shifting lever 27 is thrown down as shown in Figs. 5, 6 and 7 the spring rod 28 is bowed rearwardly and the cam is thrown to its rearward or lowering position.

The cam 26 is a metal plate pivoted between the jaws of the lever head, and has a slot 30 in which moves the pin 22. This cam also has a notch 31, and this slot and notch together with the general contour of the cam produce a curved finger 32, a head 33 and a dog 34, the finger 32 being adapted to engage the pawl 20 and the dog 34 engaging the pawl 19 while the head 33 is adapted to engage both the pawls 19 and 20 according to the position of the cam and lever. The finger 32 has an end portion 32^a projecting toward the head 33.

The operation of the parts is as follows: For raising the lift bar 12 the shifting lever 27 is pushed up as shown in Figs. 1, 2 and 3 bowing the spring rod 28 forwardly and exerting spring pressure upon the cam 26. As the operating lever 24 is forced downwardly the pawl 20 engages the ratchet teeth of the lift bar and acts as the lifting pawl, the bar sliding freely past the pawl 19 which is held against said bar by the dog 34 and the parts remain in this position during the entire movement of the lever. Upon the return of the lever the pawl 19 is held in engagement with the ratchet face of the lift bar by the dog 34 of cam 26 and acts as a holding pawl, holding the same in its raised position while the lifting pawl 20 is moved downwardly in order to engage the ratchet face of the lift bar for a further upward movement of the same. These operations are continued until the lift bar has been raised to the desired point, carrying with it the load to be raised.

When it is desired to lower the ratchet bar and the load resting thereon, the shifting lever 27 is thrown down to its lowering position as indicated in Figs. 5, 6 and 7, and the operating lever is then worked up and down as before and during this operation the pawl 20 acts as the work or load-carrying pawl and the pawl 19 acts again as the holding pawl, and the cam 26 in its shifted position serves to maintain the pawls in their proper operative positions. The pawl 20 drops freely into engagement with the ratchet bar just as the lever has com-

pleted its downward movement inasmuch as said pawl 20 is free of the finger 32 and the head 33 engages the pawl 19 as shown in Fig. 5 and holds it out of engagement with the ratchet bar so that as the lever is moved upwardly the ratchet 20 moves downwardly supporting the lifting bar which is being lowered and just as the lever reaches the end of its upward movement and the pawl 20 the end of its downward movement, the finger 32 forces the pawl 20 out of engagement with the ratchet bar and the pawl 19 being by this time freed from contact with the head 33 drops into holding engagement with the ratchet bar. As the lever is moved down again to obtain a fresh grip of the pawl 20 upon the lifting bar, said pawl 20 is kept out of engagement by the finger 32 until the pawl has been lifted free from the end of said finger as shown in Fig. 5 and as the pawl 20 drops into engagement with the ratchet bar the pawl 19 is drawn out of engagement so that the lowering operation can take place. Fig. 5 illustrates the beginning of a lowering movement, it being noted that the spring 28 has thrown the holding pawl 19 out of engagement with the lifting bar through the engagement of the part 33 with the pawl. Fig. 6, shows the lowering position in an advanced stage, it being noted that the pawl 20 has now come into engagement with the end 32^a of the finger 30 thereby causing the turning of the cam about the pivot 21 against the tension of the spring 28 and permitting the holding pawl 19 to drop into the path of the ratchet teeth. In Fig. 7, is illustrated the maximum elevated position of the hand lever 25 and the maximum lowered position of the pawl 20, it being noted that the load has now shifted from the pawl 20 to the holding pawl 19, and the pawl 20 has been kicked out of engagement with the ratchet teeth by the finger 32, the two being in engagement and the spring 28 having been put under tension as illustrated in Fig. 6. By lowering the hand lever 25, as illustrated in Fig. 5, the pawl 20 is again elevated past engagement with the finger 32 and this pawl is thereby permitted to fall into engagement with the bar to relieve the holding pawl 19 of the load, the pawl 19 being kicked out by the spring 28 as soon as the load is removed therefrom.

When there is no load upon the lifting bar it can be dropped into the standard from a raised position by simply throwing the shifting lever 27 down and raising the lever 24.

If desired the lifting bar can be instantly pulled out to its maximum height; thus making the jack a quick acting one in both directions.

Having thus described my invention, what I claim is:—

1. In a device of the kind described, the

- combination with a standard, of a lifting member movable therein, a lever pivoted thereto, working and holding pawls connected to said lever at different points, a reversible member carried by said lever, said reversible member being adapted in one position to operate upon both pawls and in the other position to operate upon one of the pawls, and a shifting lever operatively connected with said reversing member as set forth. 5
2. In a device of the kind described, the combination with a standard, of a lifting member movable therein, a lever pivoted thereto, working and holding pawls connected to said lever at different points, a reversible member arranged upon said lever, said reversible member being adapted in the lowering position to operate upon both pawls and in the raising position to operate upon the holding pawl, a shifting lever, and spring means interposed between said shifting lever and reversible member. 10
3. In a device of the kind described, the combination with a standard, of a lifting member movable therein, a lever pivoted thereto, a working and a holding pawl connected at different points with said lever, a cam arranged within the casing and adapted to operate upon said pawls, said cam being reversible and having a central head projecting upwardly between and being adapted to engage either of said pawls, said cam also having on opposite sides from the head 15 a finger and a dog for respectively engaging the pawls, and means for reversing said cam and maintaining it in its adjusted position. 20
4. In a device of the kind described, the combination with a standard, of a lifting member movable therein, a lever pivoted thereto, a lifting pawl connected to the end of the lever, a holding pawl connected to the lever at its pivotal point, a cam connected 25 also to the lever pivot, said cam having a central head projecting up between and
- being adapted to engage either of said pawls, said cam also having on opposite sides of said cam projections for respectively engaging said pawls, and a shifting lever together 50 with operative means between shifting lever and cam. 5
5. In a device of the kind described, the combination with a standard, of a lifting member movable therein, a lever pivoted thereto, a lifting pawl connected to the end of said lever, a holding pawl connected to the pivot of said lever, a cam connected also to said lever pivot and adapted to engage said pawls, a spring rod engaging said cam 55 together with means for shifting the position of said spring rod for the purpose specified. 60
6. In a device of the kind described, the combination with a standard, of a lifting member movable therein, a lever pivoted thereto, a working pawl connected to the end of said lever, a holding pawl connected to the pivot of said lever, a cam connected also to said lever pivot and adapted to engage said pawls, a shifting lever, a forked plate and a spring rod connected to said forked plate and also to said cam for the purpose specified. 65
7. In a device of the kind described, the combination with a standard, of a lifting member movable therein, a lever pivoted thereto said lever having a working and a holding pawl connected therewith, a cam also carried by said lever, said cam having 70 fingers and a head portion adapted to engage said pawls, a spring rod operative upon said cam, a pivoted plate to which said rod is attached, and a shifting lever operable upon said plate for the purpose specified. 75

In testimony whereof, I hereunto affix my signature in the presence of two witnesses.

WALTER L. WIDLAR.
